Primary Examiner — Ricky Pham(74) *Attorney, Agent, or Firm* — Tucker Ellis LLP; Carlos Garritano(57) **CLAIM**

The ornamental design for a loaf pan, as shown and described.

DESCRIPTION

FIG. 1 is a top perspective view of another embodiment of the loaf pan.

FIG. 2 is a front view thereof, the opposite rear view being a mirror image thereof.

FIG. 3 is a side view thereof, the opposite side view being a mirror image thereof.

FIG. 4 is a top view thereof; and,

FIG. 5 is a bottom view thereof.

The broken lines shown in the drawings are for illustrative purposes only and form no part of the claimed design.

1 Claim, 4 Drawing Sheets(56)
